United States Patent

Des. 242,576

Patented Nov. 30, 1976

242,576

WRAPPER

Michael H. Shulman, 45 Bruce Farm Drive,
Willowdale, Ontario, Canada

Filed Mar. 31, 1975, Ser. No. 563,587

Term of patent 14 years

Int. Cl. D15—99

U.S. Cl. D15—145

FIG. 4FIG. 2FIG. 1 is a perspective view of a wrapper showing my design taken from one side at an angle;

FIG. 2 is a perspective view thereof taken from the other side;

FIG. 3 is a rear elevational view;

FIG. 4 is a top plan view; and

FIG. 5 is a top plan view of a further embodiment thereof, in which the only difference over the embodiment of FIGS. 1 through 4 is shown.

I claim:

The ornamental design for a wrapper, as shown.
